(57) **CLAIM**

The ornamental design for a fairing, as shown and described.

DESCRIPTION

FIG. 1 is a top front perspective view of a fairing showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is another top front perspective view thereof in an environment in which it may be used.

The broken lines in the Figures show portions of the fairing and environment, and form no part of the claimed design.
